US0D1040574S

(12) United States Design Patent (10) Patent No.: US D1,040,574 S
(45) Date of Patent:  Sep. 3, 2024

(54) DRESSER

(71) Applicant: WALKER EDISON FURNITURE COMPANY LLC, West Jordan, UT (US)

(72) Inventor: Alexa Naylor, South Jordan, UT (US)

(73) Assignee: Walker Edison Furniture Company LLC, West Jordan, UT (US)

() Term: 15 Years

(21) Appl. No.: 29/830,013

(22) Filed: Mar. 9, 2022

(51) LOC (14) Cl. 06-04

(52) U.S. Cl.

USPC D6/671.1

(58) Field of Classification Search

CLAIM

The ornamental design for a dresser, as shown and described.

DESCRIPTION

FIG. 1 is a front perspective view of a dresser showing the new design;

FIG. 2 is another front perspective view thereof with drawers thereof in open positions;

FIG. 3 is a front elevation view thereof;

FIG. 4 is a back elevation view thereof;

FIG. 5 is a top plan view thereof;

FIG. 6 is a bottom plan view thereof;

FIG. 7 is a left elevation view thereof;

FIG. 8 is a right elevation view thereof;

FIG. 9 is another top plan view thereof with the drawers thereof in open positions;

FIG. 10 is another bottom plan view thereof with the drawers thereof in open positions;

FIG. 11 is another left elevation view thereof with the drawers thereof in open positions;

FIG. 12 is another right elevation view thereof with the drawers thereof in open positions;

FIG. 13 is a front perspective view of another embodiment of a dresser showing the new design;

FIG. 14 is another front perspective view thereof with drawers thereof in open positions;

FIG. 15 is a front elevation view thereof;

FIG. 16 is a back elevation view thereof;

FIG. 17 is a top plan view thereof;

FIG. 18 is a bottom plan view thereof;

FIG. 19 is a left elevation view thereof;

FIG. 20 is a right elevation view thereof;

FIG. 21 is another top plan view thereof with the drawers thereof in open positions;

FIG. 22 is another bottom plan view thereof with the drawers thereof in open positions;

FIG. 23 is another left elevation view thereof with the drawers thereof in open positions; and,

FIG. 24 is another right elevation view thereof with the drawers thereof in open positions.

The dash-dash broken lines shown in the figures illustrate portions of the dresser that form no part of the claimed design. The dash-dot broken lines in the figures define the bounds of the claimed design and form no part thereof.
